CLAIM

The ornamental design for a vehicle media hub, as shown and described.

DESCRIPTION

FIG. 1 is a perspective view of a vehicle media hub showing my new design;

FIG. 2 is a perspective view as viewed from the opposite side thereof;

FIG. 3 is a side elevational view of one side, the opposite side being a mirror image thereof; and,

FIG. 4 is a top plan view thereof.

The broken line showings of the electrical connectors, the port and the indicia on the top surface are for illustrative purposes only and form no part of the claimed design.

The broken lines, which define the bounds of the claimed design, form no part of the claimed design.
